UNITED STATES PATENT OFFICE.

WILLIAM L. JANCEY, OF CHICAGO, ILLINOIS, ASSIGNOR OF ONE-HALF TO
RICHARD SAVAGE, OF SAME PLACE.

STEAM CONFECTION-PAN.

SPECIFICATION forming part of Letters Patent No. 391,368, dated October 16, 1888.

Application filed March 8, 1887. Serial No. 230,077. (No model.)

To all whom it may concern:

Be it known that I, WILLIAM L. JANCEY, of Chicago, county of Cook, and State of Illinois, have invented certain new and useful 5 Improvements in a Steam Confection-Pan, of which the following is a full, clear, and exact description, that will enable others to make and use the same, reference being had to the accompanying drawings, forming a part of 10 this specification.

This invention relates to improvements in that class of machines used in the manufacture of certain kinds of confection wherein the same is required to be rolled and dried by the 15 application of steam-heat during the rolling process.

The object of this invention is to so construct a machine of this character that the joints and connections may be conveniently 20 kept steam and water tight in order to prevent the escape of either one.

Figure 1 is a side elevation of a machine embodying my improved features; Fig. 2, a longitudinal plan section; Fig. 3, a broken-away 25 sectional detail; and Fig. 4, a transverse section in the plane 4, Fig. 2. Fig. 5 is a broken-away side elevation showing the confection-pan in place and the steam-heating coil encircling the same.

30 In the drawings, A represents the pedestal or supporting-frame; A', the cross on which the confection-pan A² is mounted; A³, the steam-coil encircling said pan; and B, the hollow shaft, to which the cross and pan are rigidly secured. The shaft B is usually set at 35 about the angle shown, and rotates in the journal-boxes a a', the lower halves of which are formed on the pedestal, the upper halves or caps being removable.

40 B' is a bevel gear-wheel rigidly mounted on the hollow tapering shaft B. This gear-wheel engages with the corresponding pinion, B², mounted on the shaft C, set at right angles to the hollow shaft. The shaft C is provided with 45 suitable journal-bearings on the enlarged cap part of the supporting-pedestal, and has the band-pulleys mounted on the outer end thereof, which receive the belt running from the motive power. By the arrangement described 50 the required rotary motion is transmitted to the hollow shaft.

The front or larger end of the hollow or tubular shaft B is closed, the steam-supply pipe C running longitudinally through the chamber a² therein and terminating near the closed 55 end, as shown in Figs. 2 and 3. At this point the steam-pipe C screws into the inner projecting end of the hollow tapering plug a³ tapped into the shaft B and entering at right angles to the steam-supply pipe. The opening in the 60 mouth or outer end of the hollow plug a³ is somewhat enlarged and gradually contracts inwardly to the uniform passage a⁴, as shown in Fig. 3. The tapering end of the pipe a⁵ is inserted in the enlarged opening in the plug 65 a³, and is drawn into a close union with the same by means of the screw-cap b, which has a threaded engagement with the outer exterior end of the hollow plug a³, and bears against the annular shoulder b', formed on the pipe 70 a⁵, which is the starting-point of the system or coil of steam-pipes encircling and heating the confection-pan. The exhaust-plug b² and exhaust end b³ of the system of heating-pipes are connected in the same manner as that already 75 described for the supply side. The exhaust discharges into the chamber a² in the hollow shaft B, and is finally conducted off through the valve b⁴ inserted in the hollow shaft near the back end. By this means the steam supply and exhaust connection are made absolutely steam-tight, thereby dispensing with the use of the different kinds of packing commonly employed and with which it is impossible to keep the joints tight, in view of the peculiar 80 operation of the machine.

Dis a double stuffing-box, the part d of which is made to closely fit around the back end of the hollow shaft B, thus providing a large bearing for the stuffing-box, and serving to keep 85 the same in line with the hollow shaft. This stuffing-box is longitudinally adjustable on the screw-threaded bolts d' d', having the headed ends secured in the back journal-box, while the threaded ends are provided with the ad 90 justing-nuts d².

d⁴ is the larger packing-chamber, and d⁵ the packing-gland, also mounted on the bolts d' d' and having adjusting-nuts d⁶.

The packing-chamber d⁴ is located back from 100 the end of the hollow shaft, so that the packing has a circumferential bearing on the shaft and

is kept away from contact with the end of the same, and cannot be blown out, as was the case under the old arrangement. This form of stuffing-box also keeps in perfect line with the hollow shaft, and is therefore also less liable to leak.

The smaller end of the stuffing-box D is provided with the packing-chamber e, through which the steam-pipe C passes, the open end of which enters the passage e' in the packing-gland e², as also does the end of the pipe E, which conducts the live steam from the generator. The bolts e³ e⁴ adjustably connect the packing-gland e² with the smaller packing end of the double stuffing-box D. This form of a stuffing-box makes it possible to keep the parts to which it is applied perfectly tight with the expenditure of but little time and labor, the packing requiring to be renewed only at long intervals. The gear-wheel mounted on the hollow shaft is also moved forward nearer to the front end, and the front leg, F, of the supporting-pedestal curved outwardly, so as to bring the same farther under the heavier part

of the machine, in order to better balance the working parts and steady the same against undue vibration, which has a tendency to affect the steam-joints and cause the same to leak.

Having thus described my invention, what I claim as new, and desire to secure by Letters Patent, is—

The combination, with a confection-pan, of the hollow shaft B, the steam-supply pipe C', the steam-coil A³, encircling said pan, the hollow plug a³, having a tapering passage contracting inwardly and inserted in said hollow shaft and connecting the steam-pipe C' and the heating-coil A³, the screw-cap b, and the hollow exhaust-plug b', inserted in the hollow shaft at a point opposite to the plug a³, whereby steam-tight connections are formed between the parts described without the use of packing, substantially as and for the purpose set forth.

WILLIAM L. JANCEY.
